Primary Examiner—Susan Moon Lee(74) *Attorney, Agent, or Firm*—James R. Bell(57) **CLAIM**

The ornamental design for an anti-tipping holder with animal feeder jar, as shown and described.

DESCRIPTION

FIG. 1 is a perspective view of the anti-tipping holder with animal feeder jar showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
